UNITED STATES PATENT OFFICE.

JOHN E. McBRIDE, OF CLINTON, NEW YORK.

DESIGN FOR A DISH.

SPECIFICATION forming part of Design No. 20,487, dated January 20, 1891.

Application filed December 22, 1890. Serial No. 375,510. Term of patent 7 years.

To all whom it may concern:

Be it known that I, JOHN E. McBRIDE, of Clinton, in the county of Oneida, in the State of New York, have invented new and useful

5 Improvements in a Design for Dishes, of which the following, taken in connection with the accompanying drawing, is a full, clear, and exact description.

The drawing shows an isometrical elevation of my dish complete.

10 The leading features of my design for a dish consist of the separate compartments arranged in graduated sizes, an ornamental beading passing between the adjacent edges 15 of the compartments, as shown, and an ornamental beading passing around the upper lateral edge of the dish.

A represents the dish complete, and 1 1 are the compartments therein arranged in 20 graduated sizes, as shown.

2 is a beading passing on the upper adjacent edges of the compartment, as shown, and 3 is a beading passing around the upper lateral edge of the dish.

Having thus described my invention, the 25 following is what I claim as new therein and desire to secure by Design Letters Patent:

The design for a dish, as herein described and shown, consisting of compartments graduated in sizes, the beading 2, passing upon the 30 upper adjacent edges of the compartments, and a beading 3 around the upper lateral edge of the dish.

In witness whereof I have hereunto set my hand this 17th day of December, 1890.

JOHN E. McBRIDE.

In presence of—
H. P. DENISON,
C. W. SMITH.
